R. E. REARDON.
ROD FOR TARGET PRACTICE.
APPLICATION FILED MAR. 8, 1917.

1,254,069.

Patented Jan. 22, 1918.

UNITED STATES PATENT OFFICE.

ROBERT EDWIN REARDON, OF OTTAWA, ONTARIO, CANADA.

ROD FOR TARGET PRACTICE.

1,254,069.

Specification of Letters Patent. Patented Jan. 22, 1918.

Application filed March 8, 1917. Serial No. 153,477.

To all whom it may concern:

Be it known that I, ROBERT EDWIN REARDON, a subject of the King of Great Britain, and a resident of the city of Ottawa, in the 5 Province of Ontario and Dominion of Canada, have invented certain new and useful Improvements in Rods for Target Practice, of which the following is a full description.

This invention relates to improvements 10 in target practice rods of the type having a tube adapted to fit into a fire arm or the like, a spring retracted striking rod thereon adapted to be propelled to strike a suitable target.

15 The objects of the invention are to provide effective means for varying the length of the rod to enable it to be used either for magazine or single barrel practice.

Further objects of the invention are to 20 generally simplify and improve the construction of the rod to enable the various parts to better perform the functions required of them.

In the drawings,

25 Figure 1 is a longitudinal sectional elevation of an embodiment of the invention.

Fig. 2 is an enlarged sectional detail of the inner end.

30 Fig. 3 is an enlarged sectional detail of the extensible end of the striking rod.

Fig. 4 is a perspective view of the extensible end of the striking rod.

Fig. 5 is a section on the line 2—2 of Fig. 3.

35 Fig. 6 is a perspective view of the hammer section of the rod.

Fig. 7 is a section on the line 3—3 of Fig. 2.

In the drawings like characters of reference refer to like parts in the several figures.

Referring to the drawings, A represents a single metal tube adapted to extend in the barrel of the rifle or other fire arm, the head 10 of the rod being adapted to abut

45 the muzzle of the rifle and being held thereon by a suitable clip, not forming part of the present invention. The tube A contains a striking rod B formed with a forward striking section 11 and a rear hammer section 12.

The striking section is journaled at its forward end with a collar 13 in the tube A provided with a suitable striking head 14 adapted to mark a target. The striking

55 part is retracted by means of a compression

spring 15 extending from the collar 13 to the head 16 on the inner end of the rod.

The hammer section which is adapted to strike and propel the striking section, fits the inner end of the tube and comprises a 60 sleeve 18 fitting the inner end of the tube, a rod 19 extending through a plug 20 in the end of the sleeve adapted to be projected forwardly to strike the head 16, rearward movement being limited by a pin 21. 65

The rod 19 is connected at its outer end to a sleeve or socket 22 slidably mounted within the sleeve 18. The rod 19 is adapted to be spring retracted by means of a compression spring 23 extending from the plug 70 20 to the head of the sleeve 22.

25 represents the extensible end piece for the hammer portion of the striking rod having its inner end adapted to fit within the sleeve 22 and being formed on its periphery with one or more long grooves 26, and one or more short grooves 27, each pair of long and short grooves connected by a transverse groove 28.

One or more tongues 34 on the sleeve 22 80 is adapted to take into one of the grooves and at the end of the groove is adapted to be retained in position by means of a spring tongue 30 formed in the sleeve 22 and adapted to take into recesses 31 or 32 formed adjacent to the ends of the grooves 26 and 27. 85

It will be seen that when the tongue 34 is at the end of the groove 27, a greater length of the end piece 25 will project, outwardly, than when the tongue 34 is at the 90 end of the groove 26, and this will effect a variation in the length of the striking rod.

It may be stated that the formation of the tube A in a single piece adapted to contain the two parts of the striking part forms 95 a considerable advantage in practice, as it maintains a more perfect alinement and avoids the necessity of any form of joint between the parts on the rod.

As many changes could be made in the 100 above description and many apparently widely different embodiments of my invention within the scope of the claims constructed without departing from the spirit or scope thereof, it is intended that all matter contained in the accompanying specification and drawings shall be interpreted as 105 illustrative and not in a limited sense.

What I claim as my invention is:

1. In a target practice rod, a tube, a 110

spring retractable striking rod therein at one end thereof, a spring retractable hammer rod at the opposite end adapted to propel the striking rod and being itself adapted to be propelled by the hammer of the rifle.

2. In a target practice rod, a tube, a spring retractable rod therein, having an extensible end piece.

10 3. In a target practice rod, a tube, a spring retractable rod therein, having an extensible end piece, said end piece being formed with parallel short and long grooves connected by a transverse groove, a tongue 15 on the rod having a projection adapted to take into one of the grooves.

4. In a target practice rod, a tube, a spring retractable rod therein, having an extensible end piece, said end piece being 20 formed with parallel short and long grooves

connected by a transverse groove, a tongue on the rod having a projection adapted to take into one of the grooves, and means for retaining the rod in this position.

5. In a target practice rod, a tube, a spring retractable rod therein, having an extensible end piece, said end piece being formed with parallel short and long grooves connected by a transverse groove, and being also formed with a plurality of recesses, a tongue on the rod having a projection adapted to take into one of the grooves and having a spring tongue adapted to take into the recess.

In witness whereof I have hereunto set 35 my hand in the presence of a witness.

ROBERT EDWIN REARDON.

Witness:

F. E. WIMBS.
